APPARATUS FOR GRINDING THE BEVEL
EDGE OF SPECTACLE AND OTHER
LENSSES

William Adams Taig, Farnham, England

Application November 5, 1949, Serial No. 125,741
In Great Britain October 25, 1948

11 Claims. (Cl. 51—101)

1

This invention relates to improvements in apparatus for grinding the bevel on the peripheral edge of spectacle and other lenses.

In existing apparatus in which the lens or the grinding wheel is free to move axially in the bearings; the lens is engaged under pressure with a V groove in the grinding wheel with the lens or wheel freely held axially, it is not always possible to form the point of the bevel in a predetermined position, particularly, as is most prevalent, when the lens is not exactly round, without suitably shaping the groove in the wheel.

In the case of a meniscus or toric lens shaped to present day style with a considerable difference in width and height, that part of the lens which is nearer to the centre than the remainder will be curved on the edge when looked at edgewise and in such cases the apex of the bevel may be formed to one side or the other at different places around the lens.

The object of my invention is to provide a solution of this problem and to provide an apparatus which is more efficient than those at present in use and one which in edging maintains the apex of the bevel in a predetermined position.

According to the present invention apparatus for grinding the bevel on the peripheral edge of spectacle and other lenses is provided wherein axial movement is imparted to the lens during grinding to maintain the lens in correct position relative to the bevel grinding surfaces.

During grinding the lens is caused to move towards and away from the bevel grinding surfaces in accordance with the peripheral contour of the lens, and, preferably, the axial movement is effected as a result of this lens shaping movement.

An apparatus according to this invention comprises in combination grinding means for forming the bevel on the peripheral edge of the lens, lens supporting means for holding the lens in contact with the grinding surfaces of the grinding means, said supporting means imparting rotary movement to the lens, means for imparting axial movement to the lens supporting means to maintain the peripheral edge of the lens in correct alignment with the bevel grinding surfaces, and means for causing displacement of the lens supporting means to cause the lens to advance towards and recede from the grinding surfaces in accordance with the peripheral contour of the lens to produce the finished shape.

The combined axial movement of the lens

2

supporting means and its displacement towards and away from the grinding means may be effected by cams, the profile of one of said cams corresponding to the finished peripheral shape of the lens, this cam being rotatably mounted and, during its rotation, effecting the desired displacement of the lens supporting means. The shape of the other cam corresponds to the curvature of the face of the lens, and, preferably, the axial movement imparted to the lens supporting means by this cam is effected through a cam follower.

The grinding means preferably comprises two grinding wheels which are mounted separately and at an angle to one another, the peripheral grinding surfaces of the two wheels being positioned to produce the desired bevelled surfaces on the edge of the lens.

With the construction according to the present invention grinding at high speed can be effected as both the lens and the grinding wheels are securely mounted in position.

In order that the invention may clearly be understood and carried into effect an embodiment of the same will now be described with reference to the accompanying drawings in which—

Fig. 1 is a front elevation, partly in section, of apparatus according to the invention.

Fig. 2 is a plan view of Fig. 1.

Fig. 3 is a sectional view taken on the line 3—3 of Fig. 1 and

Fig. 4 is an end view taken on the line 4—4 of Fig. 2.

In the apparatus shown in the drawings the beveling of the edge of the lens 1 is effected by two grinding wheels 2, 3 each of which is secured on a driving spindle, each spindle being rotated through a belt drive, not shown, by associated pulleys 4, 5 the spindles being carried in pedestal bearing brackets 6 secured by clamping nuts 7 to a machine bed (not shown) upon which the apparatus is mounted.

The grinding wheels are set at an angle to one another, the angle between the peripheral grinding edges of the wheels corresponding to the angle of the bevel to be formed on the edge of the lens.

The lens is held in position between the grinding surfaces of the grinding wheels 2, 3 by lens supporting means, the lens supporting means imparting a rotary movement to the lens together with the required axial movement and displacement towards and away from the grinding surfaces.

As shown the lens supporting means consists of two spindles 8-9 each of which is mounted co-axially in bearing sleeves 10-11 forming part of a bracket 12.

The opposing end of each spindle is provided with a ferrule 13, a thrust bearing 14 being interposed between each ferrule and its associated spindle, and each ferrule is provided at its end with a pad 15 of rubber or other resilient material between which the lens to be ground is gripped.

The spindle 8 is slidable in its bearing sleeve and is urged towards the spindle 9 by a spring 16 surrounding the outer end of the spindle 8, one end of the spring being in engagement with a peripheral shoulder 17 formed on spindle 8, the opposite end of the spring engaging a bush 18, that is rotatable on the spindle 8, said bush 18 being fixedly secured to the sleeve 21.

The action of the spring 16 on spindle 8 is controlled by rotation of a hand wheel 20, said rotation in one direction permitting the spring to urge spindle 8 towards the spindle 9 and rotation in the opposite direction effecting movement of the spindle in the opposite direction to permit removal of a finished lens and insertion of a further lens to be bevelled.

For the above purpose the hand wheel 20 is pinned to the outer end of a sleeve 21, the inner end of which is provided with an internal flange 22 which engages with the shoulder 17 on spindle 8 to provide an abutment to control the inward axial movement of spindle 8.

The sleeve 21 is threaded externally, the thread 23 engaging with an internal thread 24 formed in a bush 25 secured in the bore of a housing 26 forming an extension of the bearing sleeve, the arrangement being such that rotation of the hand wheel 20 in one direction effects inward movement of the sleeve 21 to permit the spring 16 to urge the spindle 8 axially towards the spindle 9, and rotation of the hand wheel 20 in the opposite direction causing the sleeve 21 to move outwardly, and, through the shoulder 17 and flange 22, to move the spindle 8 axially outwardly.

The lens is rotated by the positive rotation of the spindle 9 and for this purpose this spindle is provided with a driving pulley 27 which is driven through a belt drive, not shown.

Displacement of the lens towards and away from the grinding surfaces of the grinding wheels is effected by imparting a rocking movement to the lens supporting means by a cam the profile of which corresponds to the finished peripheral shape of the lens, the cam operating against the action of a spring which urges the lens supporting means towards the grinding wheels.

For the above purpose the bracket 12 is mounted on a shaft 28 by two pairs of arms 29 and 30, which are secured by their upper ends to the brackets by headless conical point screws 31 and lock nuts 32, the lower end of each pair of arms being similarly secured by further headless conical point screws 33 and lock nuts 34 to bearing blocks 35, 36 respectively, which are carried by, and keyed to, shaft 28, the said shaft being in turn mounted in spaced bearings 37 supported by the machine bed.

To permit a positioned lens to be adjusted laterally between the grinding surfaces, the lens supporting means is movable as a whole in a lateral direction by effecting a similar movement of the shaft 28.

For this purpose the shaft 28 is urged in one direction by a compression spring 38 which sur-

rounds the shaft, the spring being compressed between one end of one of the shaft bearings 37 and a collar 39 secured to shaft 28. The shaft is movable against the spring action by operation of a hand wheel 40 having a threaded spindle 41, the threaded spindle being mounted in the threaded bore of a block 42, the end of the spindle 41 projecting through the block 42 and into a bore formed in the end of the shaft 28, this bore being provided with a thrust ball 43 against which the spindle end abuts.

The rocking movement of the lens supporting means is obtained from the rotating cam 44 which is detachably mounted on a spigot 45 projecting from one end of spindle 9, the cam urging the lens supporting means away from the grinding wheels against the action of a spring 44a one end of which is attached to the sleeve 10 the opposite end being anchored to a stud 44b carried by the machine bed.

The cam rotates with spindle 9 and is connected in driving engagement therewith by two driving pins 46 which project outwardly from a bush 47 mounted on the spigot 45, the driving pins passing through holes provided in the cam.

The cam is maintained laterally in position on the spigot 45, by a headed plunger, the head 48 of which is pressed against the opposing face of the cam by a compression spring 49 one end of which engages with the opposing end of the stem 50 of the headed plunger, the opposite end of the spring engaging with the inner end of a bore 51 formed in a sleeve 52 in which the stem 50 of the headed plunger is slidably mounted, the sleeve 52 being fixedly mounted in a bearing 53 carried by the bracket 12 of the lens supporting means.

As shown in the drawings, the headed plunger has been forced back against the action of spring 49 to permit the cam 44 to be removed and replaced by a further cam.

The periphery of the cam 44 bears against an abutment surface 54 formed on a vertical bracket 55 which is carried by one end of a spindle 56 mounted in a bore provided in a housing 57 which is secured to the bed plate of the machine, and accordingly as the cam is rotated the lens supporting means will rock with the desired motion according to the shape of the cam profile.

The position of the abutment surface 54 relative to the edge of cam 44 is variable to permit different sizes of cams to be fitted and for this purpose the spindle 56 is formed at its free end with a micrometer screw thread 57a on which a micrometer adjusting nut 58 is carried, a compression spring 59 being provided to take up any back lash in the threads.

The micrometer screw may be adjusted as grinding proceeds to effect gradual grinding of the lens to finished size or if preferred the lens may be "plunge ground" in which case the micrometer screw is adjusted to the finished size of the lens before grinding commences.

Lateral movement of the lens between the grinding surfaces of the grinding wheels is effected by a cam 60 which, as a result of the rocking motion of the lens supporting means, causes the bracket 12 to swing in one direction laterally on the pivot pins 31, the arms 29, 30 moving similarly about the pivot pins 33, the cam operating against the action of a spring 61 which operates to urge the lens supporting assembly in the opposite direction, the spring being stretched between two posts, one of which 61a is carried by one of the arms 30, the other 61b being fixed to the machine bed.

The cam 60 is detachably mounted on a spindle 60a carried on the upper end of an arm 62 the lower end of which is provided with a boss 63 by means of which the arm 62 is mounted on the shaft 28, the boss 63 being pinned to the shaft 28 so that the arm 62 and cam 60 rock with the shaft 28.

The cam 60 is provided with a cam surface 64, the shape of which corresponds to the sectional curvature of the lens to be ground and as the cam 60 is rocked lateral movement is imparted to the lens supporting means through a cam follower consisting of a roller 65 which is interposed between the cam 60 and a pressure plate 66 mounted on the free end of sleeve 52, the pressure plate forming part of a boss 67 which bears against one end of the bearing 53 so that as the pressure plate 66 is moved by the action of the roller 65 the complete lens supporting assembly receives a similar movement.

The roller 65 is carried on a pivot pin 68 mounted on the upper end of an arm 69, the said arm being provided at its lower end with a boss 69a by means of which it is mounted on a further pivot pin 70 supported in the spaced lugs 71 forming part of a bracket 72 carried by the shaft 28. The boss 69a is located on the pivot pin 70 by two rollers 70a.

The shaft 28 is freely rotatable in the bracket 72 which is held against movement by a stud 73 engaging in a support 74 projecting vertically upwards from the machine bed.

The cam 60 is removable so as to be capable of replacement by a further cam the surface of which corresponds to a lens of different sectional curvature.

As shown the arm 69 is mounted so that the same may be moved in a direction transversely of the lens supporting spindles 8-9 to permit the roller 65 to be brought into correct registration with the cam surface of cam 60.

For this purpose the pivot pin 70 is threaded for a portion of its length the threaded portion engaging with a thread formed in one of the lugs 71 the pivot pin being rotatable to adjust the position of the roller, by a knurled knob 75.

When it is desired to remove the cam 60 the lens supporting assembly is moved laterally in a direction away from this cam, i. e. to the right, see Fig. 1, and for this purpose a cam disc 76 is provided which is mounted eccentrically on a rotatable pivot 77 carried on a bracket arm 78 projecting from the bracket 72. The edge of the cam disc 76 bears against a fixed surface 79 forming part of the arm 39 so that as the cam disc is rotated due to its eccentricity the lens supporting assembly is moved laterally and held against the action of the spring 61.

The machine described above is operated in the following manner.

Cams 60 and 44 having cam surfaces corresponding to the desired finished shape of the lens to be ground are secured on their respective mountings and the lens blank 1 to be ground is positioned between the ferrules 13, the spring 16 operating to hold the lens firmly in position.

Upon starting the driving motor the lens 1 is rotated at the desired speed through the belt drive to pulley 27 and spindle 9, and the grinding wheels 2 and 3 by further belt drives to the pulleys 4 and 5.

As a result of the rotation of the cam 44 secured to the spindle 9 and the engagement of the periphery of this cam with the fixed abutment surface 54, the bracket 12 is rocked to move

the edge of the lens 1 towards and away from the grinding wheels 2 and 3, this rocking movement resulting in the correct peripheral shape of the lens 1 being obtained.

As the bearing blocks 35, 36 are keyed to the shaft 28 the same is rotated in opposite directions in accordance with the rocking movement of the bracket 12 thereby imparting a similar motion to the arm 62 and the cam 60 carried on the upper end of this arm.

The rocking motion of the cam 60 imparts through the cam follower 65 and pressure plate 66 axial movement in the direction to the lens supporting assembly against the action of tension spring 61. As the cam 60 is rocked in one direction to bring the high portion of the cammed surface into contact with the cam follower the said cam follower is rocked on its pivotal mounting to effect through the pressure plate 66 axial displacement in a direction to the right of Fig. 1 of the lens supporting assembly against the action of the tension spring 61. When the cam is rocked in the opposite direction so that the low portion of the cammed surface is brought into contact with the cam follower 65 the action of spring 61 pulls the lens supporting assembly in a direction to the left of Fig. 1. The axial displacements of the lens thus result in the peripheral edge of the same being maintained in the correct position between the grinding wheels 2 and 3.

When grinding has continued for a short period the lens should be examined to ensure that the same is being correctly ground, and if necessary the cam 44 can be adjusted by operation of the micrometer adjusting screw 57a to correct any faults which may be apparent in the peripheral shape of the lens. The cam follower may similarly be adjusted to correct any faults due to incorrect axial displacement of the lens supporting assembly.

To remove a finished lens from the machine, after stopping the machine the hand wheel 20 is rotated in a direction to cause the flange 22 engaging the shoulder 17 to slide the spindle portion 8 in a direction to the right of Fig. 1 whereby the ferrules 13 are withdrawn out of gripping engagement with the lens 1.

I claim:

1. In an apparatus for grinding optical lenses to form a bevel edge therefor, a pair of grinding wheels angularly disposed to form by their joint peripheral surfaces a V grinding surface, means for rotating said grinding wheels, lens supporting means comprising a pair of co-axially aligned spindles biased toward one another to grip a lens therebetween, means for rotating said lens supporting means, means for pivotally mounting said lens supporting means, a profiling member having a peripheral cam surface mounted on the lens supporting means and rotatable therewith, an abutment fixedly mounted for cooperation with the peripheral surface of said cammed profiling member, said lens supporting means being rockable about the pivot therefor, toward and away from the grinding edges of said grinding wheels in accordance with the radius variation of the cammed profiling member, and a cam faced member rockably mounted on the pivot for, and disposed axially and laterally of, said lens supporting means, and means between and frictionally contacting said cam faced member and said lens supporting means and pivotally mounted for movement transversely of that of said cam faced member and said lens

supporting means, said last named means being adapted, upon rocking of said lens supporting means, to impart an axial displacement thereto corresponding to the contouration of the face of the cam faced member.

2. An apparatus in accordance with claim 1, wherein means are provided for biasing said cammed profiling member toward the abutment and wherein means are provided for biasing said lens supporting means towards the cam faced member.

3. In an apparatus for grinding optical lenses to form a bevel edge therefor, a pair of grinding wheels angularly disposed to form by their joint peripheral surfaces a V grinding surface, means for rotating said grinding wheels, lens supporting means comprising a pair of co-axially aligned spindles biased toward one another to grip a lens therebetween, means for rotating said lens supporting means, a bracket having bearing sleeves respectively mounting said spindles, means for pivotally mounting said bracket, a profiling member having a peripheral cam surface mounted on the lens supporting means and rotatable therewith, an abutment fixedly mounted for cooperation with the peripheral surface of said cammed profiling member, said bracket and the lens supporting means mounted for rotation thereon being rockable about the pivot therefor, toward and away from the grinding edges of said grinding wheels in accordance with the radius variation of the cammed profiling member, and a cam faced member rockably mounted on the pivot for, and disposed axially and laterally of, said lens supporting means, and means between and frictionally contacting said cam faced member and said lens supporting means and pivotally mounted for movement transversely of that of said cam faced member and said lens supporting means, said last named means being adapted, upon rocking of said lens supporting means, to impart an axial displacement thereto corresponding to the contouration of the face of the cam faced member.

4. An apparatus in accordance with claim 3, wherein means are provided for biasing said cammed profiling member toward the abutment and wherein means are provided for biasing said lens supporting means towards the cam faced member.

5. Apparatus for grinding the bevel edge of optical lenses comprising in combination, grinding means having grinding surfaces for forming the bevel on the peripheral edge of the lens, lens supporting means for holding the lens in contact with the grinding surfaces of the grinding means, said supporting means imparting rotary movement to the lens, means for causing displacement of the lens supporting means to cause the lens to advance towards and recede from the grinding surfaces in accordance with the peripheral shape of the lens to produce the finished shape, said last-named means comprising a bracket carrying said lens supporting means, a pivotal mounting for said bracket, a profiling member having a cammed peripheral surface and mounted for movement with said lens supporting means, and an abutment mounted for cooperation with the peripheral surface of said profiling member, whereby as said lens supporting means is rotated, said bracket carrying the same is rocked about the pivot in accordance with the variations in radius of the profiling member, and means for imparting axial movement to the lens supporting means to maintain

the peripheral edge of the lens in predetermined positional relationship with the grinding surfaces comprising a cam faced member rockably mounted on the pivot for, and disposed axially and laterally of, said lens supporting means, and means between and frictionally contacting said cam faced member and said lens supporting means and pivotally mounted for movement transversely of that of said cam faced member and said lens supporting means, said last named means being adapted, upon rocking of said lens supporting means, to impart an axial displacement thereto corresponding to the contouration of the face of the cam faced member.

6. In an apparatus for grinding optical lenses to form a bevel edge therefor, a pair of grinding wheels angularly disposed to form by their joint peripheral surfaces a V grinding surface, means for rotating said grinding wheels, lens supporting means comprising a pair of co-axially aligned spindles biased toward one another to grip a lens therebetween, means for rotating said lens supporting means, means for pivotally mounting said lens supporting means, a profiling member having a peripheral cam surface mounted on the lens supporting means and rotatable therewith, an abutment fixedly mounted for cooperation with the peripheral surface of said cammed profiling member, said lens supporting means being rockable about the pivot therefor, toward and away from the grinding edges of said grinding wheels in accordance with the radius variation of the cammed profiling member, means for effectuating axial movement of the lens supporting means, comprising a cam faced member mounted axially and laterally spaced from one end of said lens supporting means and operatively connected with the pivotal mounting for said lens supporting means, whereby to rock simultaneously therewith, and a cam follower disposed between the one end of said lens supporting means and said cam faced member, said cam follower being displaceable against said end of the lens supporting means in accordance with the contouration of the face of the cam faced member as said cam faced member is rocked to axially and laterally displace the lens supporting means.

7. An apparatus in accordance with claim 6, wherein means are provided for biasing said lens supporting means into contact with said cam follower and for biasing said cam follower into contact with said cam faced member.

8. An apparatus in accordance with claim 6, wherein the center of the cam follower is in the same radial plane as the point of grinding contact between the lens carried on the lens supporting means and the grinding wheels, and is set at the same distance from the center of rotation of the lens in the lens supporting means to such point of grinding contact.

9. In an apparatus for grinding optical lenses to form a bevel edge therefor, a pair of grinding wheels angularly disposed to form by their joint peripheral surfaces a V grinding surface, means for rotating said grinding wheels, lens supporting means comprising a pair of co-axially aligned spindles biased toward one another to grip a lens therebetween, means for rotating said lens supporting means, a bracket having bearing sleeves respectively mounting said spindles, means for pivotally mounting said bracket, a profiling member having a peripheral cam surface mounted on the lens supporting means and rotatable therewith, an abutment fixedly mounted for cooperation with the peripheral surface of said profiling member, whereby as said lens supporting means is rotated, said bracket carrying the same is rocked about the pivot in accordance with the variations in radius of the profiling member, and means for imparting axial movement to the lens supporting means to maintain

tion with the peripheral surface of said cammed profiling member, said bracket and the lens supporting means mounted for rotation thereon being rockable about the pivot therefor, toward and away from the grinding edges of said grinding wheels in accordance with the radius variation of the cammed profiling member, means for effectuating the axial movement of the bracket and the lens supporting means carried thereon, comprising a cam faced member mounted axially and laterally spaced from one end of said lens supporting means and operatively connected with the mounting for said lens supporting means, whereby to rock simultaneously therewith, and a cam follower disposed between one end of said lens supporting means and said cam faced member, said cam follower being displaceable against said end of the lens supporting means in accordance with the contouration of the face of the cam faced member as said cam faced member is rocked to axially and laterally displace the lens supporting means.

10. An apparatus in accordance with claim 6, wherein means are provided for adjustably mounting the cam follower, whereby its path of

travel on the surface of the cam faced member may be varied to correspond with the engagement of the lens edge with the grinding surface.

11. An apparatus in accordance with claim 6, wherein means are provided for relatively adjusting the spindles of the lens supporting means, whereby the same may be axially movable to initially permit adjustment of the position of the lens carried thereon between the grinding surfaces.
